UNITED STATES PATENT OFFICE.

CYRUS BALDWIN, OF MANCHESTER, NEW HAMPSHIRE, ASSIGNOR TO STARK MILLS.

LOOM FOR WEAVING BAGS.

Specification of Letters Patent No. 8,553, dated December 2, 1851; Antedated August 30, 1851.

To all whom it may concern:

Be it known that I, CYRUS BALDWIN, of the city of Manchester, in the county of Hillsborough in the State of New Hampshire, have invented certain new and useful Improvements in Power or Other Looms, for weaving two or more thicknesses of cloth at the same time and weaving two or more of the thicknesses of the cloths so woven together, so as to unite them at given distances across the cloth, two or more of the cloths being woven together at one or both selvages or otherwise, so as to form one thickness of cloth at such given distances as may be required to form the bottoms or sides of bags, sacks, or other articles without stopping the loom to make the changes necessary, as has been the practice heretofore; and I do hereby declare that the same is described and represented in the following specification and accompanying drawings.

The nature of my invention and improvement consists, in so constructing and arranging the several parts of a loom, that when it has woven the required length of cloth, to form a bag or other article, a part of the cams that operate the heddles will stop, while the others proceed, until they arrive to such a relative position in regard to the cams that stopped; that if the cams that stopped were put in motion, the warps which have been woven into two thicknesses of cloth, would be woven into one; when the cams that stopped proceed, and so weave all the warps into one thickness of cloth, as to connect the two cloths together and form the bottom or side of a bag or other article, as may be required. When a proper length of the warps have been woven into one thickness to form the bottom or side required, or the bottoms or sides required, the cams that stopped before, stop again, until the cams in motion arrive to such a relative position in regard to the cams that stopped, that if the cams that stopped are put in motion, the loom will weave two thicknesses of cloth as before; then the cams that stopped proceed and the loom weaves cloth of two thicknesses the length required; when it will change as above described, and weave all the warps together and form one cloth as required. The loom making all the changes necessary to weave the warps alternately into two cloths or one as required; making all the changes while in motion

running at the rate of 150 picks per minute without the aid of the attendant.

To enable others skilled in the art to make and use my invention, I will proceed to describe its construction and operation.

Figure 1 is a view of the front of the loom. Fig. 2 is a view at the right hand end. Fig. 3 represents the cams, showing the grooves in a position to weave double cloth; the dotted lines on 13 and 14 show the position the cams are moved to, to weave all the warp together, and make single cloth. Fig. 4 represents a section of the shaft I³ while I² and the parts connected with them cut through the line 33. Fig. 5 is a top view of the stand K², pawl m, etc.; Fig. 6, one of the treadles and the parts that connect it to the harness frame.

The same letters refer to like parts in all the drawings, and when a piece is partially obscured the same letter may be upon it in two or more places.

A, A, posts; A', breast beam; A², top rail; A³, end girt; A⁴, back girt; B, the lathe hung and operated in the usual manner, by the sweeps B' and the crank B² of the shaft B³, which turns in appropriate bearings on A², driven by a belt applied to the pulley B⁴. Upon the opposite end of the shaft B³ there is a gear C, which drives the gear C', and turns the shaft C², with the cams C³ C⁴, which act upon the levers C⁴ C⁴, connected to the picker staffs D D; to traverse the pickers and throw the shuttles. D' the yarn beam retained by the screw l⁵ on the shaft D², acting on the wheel t⁶ on said beam. D³ the yarn roller (represented by dotted lines) supported by the levers D⁴ which act upon the sector E; which sector is acted upon in its turn by the spring E', acting upon the arm E² of the sector. The above mentioned parts may be made and operated as many of the looms at present in use are made and operated.

The gear F upon the shaft C², drives the gear F' which turns the shaft F²; these wheels are inside of the girt A³, which supports one bearing of the shaft, the other being upon the stand F³ fastened to the back girt A⁴. The grooved cams 1, 2 are fastened to the shaft F², and traverse the rollers on pins in the levers 3, 4, to vibrate them upon the screws in the stand F⁴, fastened to the back girt. One of the rollers and the pin it turns upon is shown in dotted lines at e².

The heddle frames 5, 6, 7 and 8 made as represented with a perpendicular bar at each side joined to a horizontal one across the bottom and an arched rod across the top, and are sustained in their places by the stands G G, and by the cleats α' , α' , shown in dotted lines, fastened to the inside of the girts A³. The stands 9 and 10 are fastened to the bottom bars of the heddle frames 5, 6, and are connected to the levers 3, 4 by the straps 11 and 12, which pass around the pivots of the stands 9, 10, and through the ends of the levers 3, 4; and the ends lap so that a screw passes through each of them and through the pieces of wood t⁴ fitted between the pivots of the stands and the ends of the levers; so as to communicate a positive motion in each direction to the heddle frames 5, 6 and to the heddles α^2 , fastened to the heddle frames by the rods a³ a³. The lever 4, wheel e², and strap 11, stand 9 and the piece of wood 1⁴ and the bottom of the harness frame 5 are all represented in Fig. 6.

The shaft G' turns in bearings fastened to the posts A, A, and forms the fulcrum of the lever G²; which is vibrated by the connecting rod G³, attached to the sword of the lathe and traverses the catch G⁴ which acts upon the wheel H, fastened to the shaft G' to turn it. An end view of the above named parts is represented in Fig. 7. The friction wheel H' is fastened to the same shaft and is acted upon by the spring a⁴ under the block b which is forced down by the screw b', turning in the breast beam A', so as to graduate the friction upon the wheel.

The sprocket wheel H² is fastened to the shaft G', and acts upon the chain H³ which drives the sprocket wheel b², to turn the roller b³ in the stands b⁴ b⁴ upon the breast beam; and in connection with roller C in the same stands takes up the cloth as it is woven. The rollers b³ and c being geared together by the wheels c' c' partially shown in Fig. 2. The roller b³ is pressed against the cloth by the springs c² c² which are drawn against it by the screws which pass through them, and into the stands b⁴ so as to adjust the pressure.

The wheel H⁴ is fastened to the end of the shaft G' and the pin C⁴ in it acts upon the teeth of the wheel I; which turns on the stud d fastened into the post A. The wheel I has a circular groove d¹ in it that holds the pin d², in the rod d³; one end of which is slotted and traverses on the stud d, and is acted upon by the spring d⁴ which acts against the collar e, fastened to the rod d³ and against the knee e¹, one end of which surrounds the rod d³ and the other end is perforated to fit the stud d, and is fastened to it. The groove d¹ has two notches h h¹ cut toward the periphery and two h² h³ cut toward the center; in which the pin d² tra-

verses as will be hereafter described. The wheel I has one tooth with an inclined plane s in front of it against which the pin c⁴ acts and propels the wheel faster than when it acts against the teeth cut straight to the center.

The wheel I¹ upon the right hand end of the Shaft C² upon the outside of the girt, drives the wheel I² upon the shaft I³, which turns in bearings similar to those described for the opposite shaft F², and has the grooved cams 13, 14 upon it, that traverse the rollers (one of which is represented by dotted lines at a, Fig. 1,) on the pins in the levers 15, 16 to vibrate them upon the screws in the stand I⁴ fastened to the girt A⁴. The opposite ends of the levers 15, 16 are connected to the heddle frames 7, 8, by similar fixtures to those already described as connecting the levers 3 and 4, with the heddle frames 5, 6. The heddles e⁸ are connected to the frames 7, 8 by the rods e⁴ e⁴ similar to those heretofore described. The levers 15, 16 are above the shaft I³ and the levers 3, 4 are below the shaft F² heretofore described.

The cog wheel I² turns freely upon the shaft I³ and has a projection, or flange f upon it to which the spring f¹ is fastened; which spring f¹ has a stiff projection n on the end, which plays through a notch in the projection f into the notches m¹ m² m³ m⁴ in the wheel K, which turns just inside of the projection f as represented by dotted lines, and is fastened to the shaft I³. There is a pin r projecting from the spring f¹ which raises the projection n when the pawl m is forced into one of the spaces o¹ o² o³ o⁴ in the rim K¹ upon the side of the wheel K. The pawl m in being connected to the end of the rod d³ opposite to the end heretofore described; which pawl m vibrates on a pivot that projects through the stand K² fastened to the top rail A². A section of the shaft I³ wheels I² and K with the rim K¹ are seen cut through the line z z of Fig. e in Fig. 4. And a top view of the stand K² pawl in with the sections of the rod d³ and top rail A² are represented in Fig. 5.

The loom being completed as above described, the warp put in and properly adjusted, a shuttle supplied with weft put in and a belt applied to the pulley B⁴, the loom is put in operation, the lathe and shuttle operate in the usual manner; the yarn beam yielding the warp which is let off as it is required by a motion taken from the lathe. The cams being arranged as shown in the drawing (Fig. 3.) Cam 1 raises the heddle frame 5 with one fourth of the warp, when the shuttle carries a thread of weft across for the upper cloth, when the cams 2 and 13 raise the heddle frames 6 and 7 taking up one half the warp, when the shuttle carries a thread of weft across for the lower cloth; when the cams 1

and 13 take down the heddle frames 5, 7 with one half the warp; then the shuttle takes the weft across for the upper cloth, then the cams 1 and 14 raises the heddle frames 5 and 8 with one half the warp; when the shuttle carries the weft across for the lower cloth, then the cams 2 and 14 descend with one half the warp; the cams have now made an entire revolution the heddle frame 5 with one fourth of the warp being raised, which is the same position the warp was in the first time the shuttle crossed; and if the loom is kept in operation and the shuttle supplied with weft, the loom will 10 continue to weave the cloth double and joined at the selvages, the shuttle delivering a thread of weft for the upper and lower cloth, alternately carrying the weft from one to the other at the selvages; thus weaving 15 the two thickness of cloth until the rollers b^3 and c which take up the cloth have measured the length of double cloth required; and the tooth s of the wheel I is acted upon by the pin c^4 ; in the wheel H, and the pin 20 d^2 in the rod d^3 , is forced into the notch h by the spring d^4 , and the pawl m catches under the pin r , and into the space o^2 , in the rim K and raises the projection n out of the notch m^4 in the wheel K, and allows 25 30 it to stop with the shaft I³, and cams 13, 14 until the grooves in the same come opposite to the grooves in the cams 1, 2, as represented in dotted lines Fig. 3; in the meantime the pin r has passed over the pawl m , and the projection n has caught in the next 35 notch m^3 further forward in the wheel K, and put the shaft I³ and cams 13, 14 in motion; the grooves in the cams 1, 14 being opposite to each other and the cams 2 and 13 40 being also opposite the loom weaves all the warp into single cloth; connecting the two thicknesses of cloth previously woven together for the length required. As the pin r passes over the pawl m it depresses the 45 short end p raising the opposite end and pushing the pin d^2 out of the notch h and against the inclined side of the notch h^2 propelling the wheel I forward so that the pin d^2 , as it is forced out of the notch h^2 50 catches on that portion of the groove d^1 , that is between the notches h h^1 , so that the wheel I is propelled by the pin c^4 , until the pin d^2 slips into the notch h^1 , and the pawl m catches under the pin r and raises the projection n allowing the wheel K and cams 13 55 and 14 to stop; until the projection n arrives to and enters the notch m^1 in the wheel K, and cams 13, 14 proceed and weave double cloth; the cam 13 having taken the position 60 in reference to the cams 1, 2 that was occupied by the cam 14 when the loom wove double cloth before and the cam 14 has assumed the position that cam 13 occupied.

When the pin r passed over the pawl m , 65 it depressed the end p shoving the pin d^2

out of the notch h' and against the inclined side of the notch h^3 propelling the wheel I so that the pin d^2 , as it was brought back by the spring d^4 , caught on the groove d' , so that the pin c^4 propels the wheel I, and the loom weaves double cloth; until the rollers b^3 and c have measured the required length and the wheel I has been propelled so near around, that the pin d^2 is forced into the notch h when the loom weaves single cloth 70 75 as heretofore described to connect the cloths together for a proper distance and then changes to weaving double cloth again as heretofore described. The tooth s of the wheel I is made with an inclination forward so that the pin c^4 will propel the wheel I faster, while the change from double to single cloth, and from single to double cloth is being made.

The length of double or single cloth may 80 85 be varied when required, by increasing or diminishing the number of teeth in the wheel I, and by changing or increasing the notches cut from the groove d' or both.

The rollers b^3 and c which take up the 90 cloth which is represented by the red line, receive their motion as follows, viz., the lever G^2 which vibrates on the shaft G' , and is acted upon by the connecting rod G^3 , connected to it and to the sword of the lathe, 95 which operates it, and traverses the catch G^4 , which acts upon the wheel H fastened to the shaft G' , which has a sprocket wheel H^2 upon it that acts upon the chain H^3 , and turns the roller b^3 by the wheel b^2 , fastened 100 to it, which roller turns the roller c by the wheels c' c' . If the catch G^4 moves the wheel H so that the rollers b^3 and c draw the cloth faster than it is woven, and driven over by the reed, the elasticity of the cloth 105 and warp in connection with the springs E' , and the springing of the warps by the heddles will pull the cloth, and turn the rollers back as the catch G^4 yields; the spring a^4 upon the wheel H' being properly adjusted 110 to allow it to do so; so that the catch G^4 will not take another tooth of the wheel H until a sufficient quantity of weft is put in to allow it to move the wheel H again. To weave twilled cloth an additional number 115 of cams, levers, heddles, etc., may be used; and to increase the number of thicknesses of cloth, additional shafts with cams, etc., may be added, or cylindrical shafts may be put upon the cam shafts, and turn upon them, 120 operated by additional gearing carrying additional cams to operate the heddles required; and additional fixtures, similar to those described that change the relative position of the cams, may be added; to change 125 the relative position of the additional cams, while the loom is in operation; to weave such a number of the thicknesses of cloth together as may be required.

Instead of two short shafts for the cams. 130

there may be one shaft having part of the cams attached to it and to turn loose in the other cams which may be connected to a wheel like K fastened to the shaft; so that 5 the relative position of part of the cams in reference to the others, can be changed while the loom is in motion.

The cams and levers and heddles may be so arranged as to weave double cloth, and 10 weave two selvages at one side of the loom, and weave the two thicknesses of cloth together at the opposite side, to form the bottom of a bag; and weave the two cloths together at given distances to form the sides, 15 so that the mouth of the bag will be surrounded by a selvage.

I contemplate weaving bed and mattress ticks whole, so as to cut a slit in the center of one side; and turn them inside out, and 20 then fill them through the hole and sew it up to complete them.

What I claim as my invention and desire to secure by Letters Patent—

1. Is placing the cams upon one or more 25 shafts in such a manner that they can be

moved, so as to change their relative position in regard to each other with or around the shaft if upon separate shafts; or around the shaft if upon the same shaft; in combination with the devices substantially such as 30 are herein described, or their equivalents, for releasing, changing and holding said cams as may be required for the purposes set forth in the foregoing specification.

2. Is the pin r on the spring f' in combination with the pawl m , or their equivalents, to force back the rod d^3 and propel the wheel I by the pin d^2 acting against the inclined sides of the notches h^2 h^3 so that the pin d^2 will fall back on the groove d' , and 35 40 allow the wheel I to be propelled by the pin c^4 .

In testimony whereof, I have hereunto signed my name before two subscribing witnesses.

CYRUS BALDWIN.

Witnesses:
